Primary Examiner — Elizabeth A. Albert*(74) Attorney, Agent, or Firm* — The Van Winkle Law Firm; William G. Heedy(57) **CLAIM**

The ornamental design for a planter, as shown and described.

DESCRIPTION

FIG. 1 is a perspective view of a planter showing my new design;

FIG. 2 is a perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines showing the inside of the planter are included for the purpose of illustrating portions that form no part of the claimed design.

1 Claim, 8 Drawing Sheets(56)
